FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

CIGAR-HOLDER AND ASH-RECEPTACLE.

1,312,530.

Specification of Letters Patent.

Patented Aug. 12, 1919.

Application filed August 28, 1916. Serial No. 117,157.

To all whom it may concern:

Be it known that I, FRANZ A. FULLER, a citizen of the United States, residing in the city of Newark, in the county of Essex and State of New Jersey, have invented certain new and useful Improvements in Cigar-Holders and Ash-Receiptacles, of which the following is a full, clear, and exact description, such as will enable others skilled in the art to which it pertains to make, construct, and use the same, reference being had to the accompanying drawings, and to characters of reference thereon, forming a part of this specification.

My invention has reference to improvements in combined cigar holder and ash receptacles, for the placing therein of cigar ashes, burnt matches, and the like, and provided with means for supporting cigars, cigarettes, etc.

The invention relates more particularly to a novel construction of a combined cigar holder and ash receptacle, comprising an upper and a lower shell, the lower shell at its upper edge being provided with holding means, and the upper shell at its lower edge being provided with locking means, said locking means having locking engagement with said holding means. The principal object of this invention therefore, is to produce a cigar holder and ash receptacle, for the purposes above enumerated, which shall be neat in appearance, and shall be of a simple, strong and durable construction, thus providing a device consisting of but two parts, said parts being of such shape as to lend themselves readily to manufacture by the use of suitable punches and dies from ordinary sheet metal, and can be readily and conveniently taken apart for the purpose of removing the ashes, burnt matches, etc., and then again assembled.

My present invention therefore consists in the novel construction of a combined cigar holder and ash receptacle embodying the principles hereinabove mentioned, and of a character to be more fully described in the following specification. This invention consists furthermore in the several novel arrangements and combinations of the various parts, as well as in the details of construction of the same, all of which will be hereinafter more fully set forth and then finally

embodied in the clauses of the claim which are appended to this specification.

55

The invention is fully illustrated in the accompanying drawings, in which—

Figure 1 represents a plan view of the preferred form of my improved device.

Fig. 2 represents a side elevation, partly in section, taken on lines $x-x$ of Fig. 3.

Fig. 3 represents an under plan view; and

Figs. 4 and 5 represent fragmentary views of the upper and lower sections, illustrating the locking and holding means, by means of which the sections are secured together.

Similar characters of reference are employed in all of the above described views to indicate corresponding parts.

70

Referring now to the said drawings, the reference character 1 indicates the complete device, which consists essentially of an upper and lower section, namely, the lower ash receptacle 2, and the upper cigar holder 3, secured to said ash receptacle in a manner to be hereinafter described, said cigar holder having an aperture 4 through which ashes, matches, etc., may pass into the ash receptacle 2.

80

The upper section or cigar holder 3 is blanked out from a single piece of suitable sheet metal, and provided at its circumferential edge with a plurality of integral projections 5, preferably four in number, as shown on the drawings, said projections 5 being adapted to be turned over on the inside of said holder 3 to form guides 5', the center of each projection 5 having a depression 6 formed therein, which projections and depressions form the locking means for holding said cigar holder on the ash receptacle 2. The upper surface of said holder 3 is provided with a raised annular portion 7 forced out from the metal when the holder is blanked out, and this raised annular portion 7 is provided with depressed portions 8, for the purpose of receiving cigars, cigarettes, etc., and for the purpose of permitting the ashes therefrom to drop into the ash receptacle 2, the center of the holder 3 is cut away, forming a circular aperture 4, which permits said ashes to drop into the lower portion of the device 1.

85

The lower section or ash receptacle 2 is formed as shown in the drawings, of a sin-

100

105

gle piece of suitable sheet metal, the circumferential edge being provided with a plurality of integral holding ears 10, extending outwardly therefrom, said ears 10 being 5 four in number to correspond with the integral projections 5 formed on the cigar holder 3. The center of each of said holding ears 10 is apertured as at 11, which apertures are designed to receive the depressions 6 of 10 the locking means 5, when the two sections are brought together to form the completed cigar holder and ash receptacle.

The outside peripheral edge of the cigar holder 3 is turned down, forming a flange 12, which flange forms a guide for centering said holder 3 on the ash receptacle 2, the outside edge of the holding ears 10 of said receptacle 2 being in close proximity to the inside edge of the flange 12, and upon the sections being turned in opposite directions, each of said ears will engage with one of the turned-over projections on the holder 3, and will be interlocked therein and guided thereby, so that further rotation in the same direction will force the ears 10 into the guides 5 of the turned-over projections 5 and cause the depressions 6 to snap into engagement with the apertures 11, thus securely locking the two sections together and preventing accidental separation thereof.

Owing to the plain contour of the cigar holder 3 outside of the raised annular portion 7, it lends itself admirably for advertising purposes, and also, the inclined portion leading to the center aperture 4, for the same reasons, lends itself for the same purpose.

Experience has demonstrated that the organization above described is a highly efficient one, and while the device described is 40 the preferred embodiment of my present invention, I do not care to restrict myself to the exact details of construction, combination and arrangement herein set forth, it being obvious that minor variations thereof, not 45 involving the exercise of invention, may be made by any skilled mechanic, and such departures from what is herein described

and claimed, I consider within the scope and terms of my claims.

I claim:

1. As an article of manufacture, a combined cigar holder and ash receptacle, comprising an upper apertured shell forming the cigar holder, and a lower shell forming the ash receptacle, said upper shell being provided with a circumferential centering flange, portions of said flange being turned over on the inside of the holder to form guides, the lower shell being provided with a plurality of ears extending outwardly from the circumferential edge of said lower shell, designed to be received by said guides and to have frictional holding engagement therewith, when the two sections are rotated in opposite directions. 50 55 60

2. As an article of manufacture, a combined cigar holder and ash receptacle, comprising an upper shell forming the cigar holder, and a lower shell forming the ash receptacle, said upper shell being provided with a raised annular and apertured portion, the raised portion being provided with depressed portions for the reception of cigars, said upper shell being further provided with a circumferential centering flange, said flange being provided with a plurality of integral projections extending inwardly from the circumferential edge of the holder, each projection being provided with holding means thereon, the lower shell being provided with a corresponding plurality of ears extending outwardly from the circumferential edge of the said lower shell, each ear being provided with receiving means, the holding means in said projections adapted to snap into engagement with the receiving means in said ears when the two sections are rotated in opposite directions. 65 70 75 80 85

This specification signed and witnessed this 25th day of August, 1916.

FRANZ A. FULLER.
